COVER FOR POLISHING WHEELS

Anthony Coniglio, Chicago, Ill.

Application February 13, 1935, Serial No. 6,284

12 Claims. (Cl. 15—230)

This invention relates to improvements in covers for polishing wheels and a method of attaching the same, although the invention may have other and various uses and purposes as will be 5 apparent to one skilled in the art.

In the past, certain cloths for polishing wheels, which are customarily made of a light canvas or drill cloth, have been developed. However, all 10 of these formerly known covers of which I am aware have been objectionably difficult to attach to a polishing wheel. This difficulty of attachment was caused mainly by the construction of the cover. The commonly known cover of this type is one comprising a strip of drill cloth with 15 pleats or folds formed along each side margin. The pleats or folds are maintained in the cloth by a line of stitching which also serves to hold a string or cord secured to the cloth. This string runs up one side edge of the cloth, forms a loose 20 loop free from the cloth over one end thereof, and then is secured to the cloth down the other side edge thereof, thus leaving two free string ends at one end of the cloth. In attaching such a cloth to a wheel, the loose loop was inserted in a groove 25 or indentation in the surface of the polishing wheel and with the other end of the cloth held in the hand, the wheel was rotated until the cloth was wound therearound, whereupon the loose ends of the string must be pulled to tighten 30 the cloth around the wheel, and then these loose ends were tied around the shaft of the wheel on opposite sides of the wheel. However, the central portion of the cloth was much longer than the side edges of the cloth due to the pleats and 35 folds adjacent the side edges, and consequently much difficult and tedious smoothing of the cloth was necessary to have a tight fit over the working surface of the wheel. Further, in view of the fact that the string was held directly to the cloth by 40 a line of stitching, portions of the string frequently became loosened from the cloth during the tightening and thereupon the cloth must be cast aside or used with a portion thereof loosely flapping with the revolutions of the wheel. The 45 difficulty of attachment, the necessary and tedious smoothing of the cloth and the tieing of the free ends of the string required an undesirable and expensive amount of time. This, taken together with the frequent injury to the cloth resulting 50 from a loosening of the string, rendered the use of the cloth objectionably expensive. Economy is highly essential, especially when these cloths are used on polishing wheels in the shoe repair industry.

55 In another instance, a previously developed

cover for a polishing wheel was provided along each side edge thereof with a hem through which a string was threaded. In attaching such a cover or cloth, it was necessary to tie the free ends of both strings, one on each side of the wheel, to hold the cover in position. 5

All other previously developed covers of which I am aware were very similar in construction to those above mentioned, and were open to the same objections of difficulty in use, expense of manufacture, and wastage due to injury to the cover when applying the same.

With the foregoing in mind, it is an object of this invention to provide a cover for polishing wheels and the like, which cover is exceedingly 15 simple to attach to a wheel and very economical to make.

It is another object of this invention to provide a polishing wheel cover constructed in such a manner that it is not necessary to tie the free 20 ends of the cord or draw string by which the cover is tightened around the wheel to hold the cover in position.

It is also an object of this invention to provide a polishing wheel cover so constructed as to provide a tight fit over the working surface of the wheel immediately upon application without the necessity of hand smoothing the cover during attachment. 25

The invention includes these and other features 30 of construction and having the above objects and aims, others of which will become more apparent from the disclosures hereinafter.

On the drawing:

Figure 1 is a plan view of a device embodying 35 principles of the present invention.

Figure 2 is a greatly enlarged fragmentary view of a portion of the structure shown in Figure 1.

Figure 3 is a fragmentary vertical sectional view taken substantially as indicated by the line 40 III—III of Figure 2.

Figure 4 is a sectional view of the character of Figure 3 illustrating a slightly different form of construction.

Figure 5 is a vertical sectional view illustrating 45 the first step in applying a cover of the present invention upon a polishing wheel.

Figure 6 is a view of the character of Figure 5 illustrating a more advanced step in the attachment of the cover to the wheel. 50

Figure 7 is a view of the character of Figures 5 and 6 illustrating a further step in the attachment of the cover to the wheel.

Figure 8 is a fragmentary front elevational view of a polishing wheel equipped with a cover 55

embodying principles of the present invention, showing the same ready for use.

As shown on the drawing:

In the illustrated embodiment of the present invention, there is seen a polishing wheel cover generally indicated by reference numeral 10. This cover comprises a substantially rectangular body 11 made of any suitable material, drill cloth being highly desirable, although flannel, light 5 canvas, felt and similar fabrics may also be used. The body 11 is preferably smooth without any pleats, ruffles, folds or similar body formations. This body 11 is preferably provided along each side edge thereof with stitching 12, leaving the 10 end edges 13 and 14 respectively, free, as best 15 seen in Figures 1 and 2.

The stitching 12, as seen more clearly in Figure 2, is preferably of the overedge type, providing substantially a tubular guideway along the 20 edge of the fabric. The stitching is formed around a continuous draw string 15 of any desirable material, such, for example, as light twine, and the draw string is free both from the stitching and from the body 11. Across the end 14 25 of the body 11, the stitching is chained off, as indicated at 16, to form a loose arc over this end of the fabric, and then the stitching continues in overedge style along the opposite side of the fabric, the stitching being preferably continuous 30 up one side of the fabric, through the chained off portion 16, and down the other side of the fabric. The draw string 15 is loose within the stitching throughout the entire length thereof, and as seen best in Figure 1, the free ends of the draw string 35 project beyond the fabric where they may be easily grasped by the hands of a user.

In Figure 4, I have shown a slightly different form of construction, wherein a small hem 17 is made in the fabric along the edge thereof. This 40 hem does not change the character of the stitching 12, but results in a slight strengthening of the body 11. In this figure, the draw string 15 is disposed beneath the opposite side edges of the fabric rather than beyond these edges, and is contained loosely within the stitching, free from both 45 the stitching and the fabric. The operation of the structure shown in Figure 4 is the same as that disclosed in Figures 1, 2 and 3.

The present invention lends itself to a new and 50 novel method of attaching a cover to a polishing wheel. The method of attaching the cover to a wheel is seen best in Figures 5 to 8, inclusive. In these figures, there is shown a shaft 18 upon which is mounted a polishing wheel 19 of any 55 desired construction or character. In most of these polishing wheels, grooves or indentations 20 are formed in the working surface of the wheel to add to the polishing effect of the wheel. In the event such grooves do not appear in the surface of the wheel, a suitable groove or indentation 60 may be provided in an obvious manner, or the invention may be applied upon a smooth-surfaced wheel.

In applying the cover 10 to the wheel 19, the 65 cover is first centered with respect to the working surface of the wheel and the chained off loop 16, together with that portion of the draw string 15 contained therein, is inserted in one of the grooves 20, or merely engaged with a portion of the work 70 surface, the cover being held at full length substantially tangentially to the wheel, as seen in Figure 5. The wheel is next turned away from the operator to wind the cover around the working surface of the wheel, as indicated in Figure 6. 75 Next, the two free ends of the draw string 15 are

pulled by the operator, thus ruffing the side margins and causing the cover to tightly embrace the wheel, as seen in Figure 7. It is not necessary that the free ends of the draw string be tied to anything, the friction of the string within 5 the stitching 12 being sufficient to maintain the cover firmly in position upon the wheel until the wheel flanges 21 (Figure 8) have been placed in position. The flanges 21 are of standard construction and of the character commonly used 10 with polishing wheels in the shoe repair industry. As seen best in Figure 7, these flanges overlie the marginal edge of the cover and when clamped into position upon each side of the wheel, they hold the cover in position upon the wheel. 15

It will be noted that during the positioning of the cover upon the wheel, especially during the winding of the cover around the wheel, all of the strain upon the cover is carried by the chained off stitching 16 so that there is no tendency to pull 20 the draw string 15 through the stitching and render the free ends of the string unavailable. It will also be noted from Figure 8, that upon the tightening of the draw string the cover smoothly 25 form fits the working surface of the wheel and does not require hand smoothing to provide an even surface for polishing.

The cover may be as easily removed from the wheel. It is a simple expedient to release the flanges 21, grasp the end of the body portion 11, 30 and by pulling upon this end the wheel will rotate towards the operator, the cover being freed upon a sufficient turning of the wheel.

From the foregoing, it is apparent that I have provided a new and novel cover for polishing 35 wheels and the like which is simple in construction, economical to manufacture, very durable, not prone to injury on application, and which may be extremely easily applied to a wheel. It is also apparent that I have provided a new and 40 novel method of attaching the cover to a polishing wheel, providing a devolved saving in time and labor over anything known heretofore, together with a preserving of the cover material.

I claim as my invention:

1. As an article of manufacture, a cover for 45 polishing wheels and the like, comprising a strip of polishing material, a draw string, and stitching along a side edge of said strip of such a character as to loosely embrace said draw string.

2. As an article of manufacture, a cover for 50 a polishing wheel and the like, comprising a strip of fabric, overedge stitching along both side edges of said strip, said stitching being chained off free from the fabric across one end of the strip thus forming a tube, and a draw string in the tube formed by said stitching.

3. As an article of manufacture, a cover for a 55 polishing wheel and the like, comprising a flat strip of flexible polishing material, a continuous draw string disposed adjacent the edge of the strip and slidably along both long edges of the strip and looped across but free from an end of the strip, and overedge stitching holding said draw string in position along the side edges of 60 said strip.

4. As an article of manufacture, a cover for a 65 polishing wheel and the like, comprising a flat strip of flexible polishing material, a continuous draw string disposed adjacent the edge of the 70 strip and slidably along both long edges of the strip and looped across but free from an end of the strip, and overedge stitching holding said draw string in position along the side edges of 75 said strip, said stitching being chained off to form

a tube free of the strip for that portion of the draw string across the end of the strip.

5. As an article of manufacture, a cover for a polishing wheel and the like, comprising a flat strip of fabric having a relatively narrow hem along the side edges thereof, overedge stitching along said edges, and a tightening string loosely held adjacent said fabric by said stitching.

6. In combination, a polishing wheel, and a cover on said wheel comprising a flat strip of 10 polishing material, a draw string, and stitching along the side edges of said strip loosely embracing said draw string, said stitching being continued beyond an end of said strip to form a 15 tubular enclosure for a looped portion of the string, said tubular enclosure being engaged with the work face of said wheel and the cover wrapped around the wheel, said draw string being drawn on each side of said wheel to hold the cover 20 thereupon.

7. In combination, a polishing wheel, and a cover thereon, said cover being flexible and wider than the work face of said wheel and wound around said work face, a draw string loosely carried by stitching on said cover and drawn on each 25 side of said wheel to hold said cover in position, and flanges associated with said wheel and moved into tight engagement with the marginal portions of said cover to maintain the cover on the wheel.

30 8. A flexible sheet material cover for a polishing wheel having a draw string in the shape of a U and having its legs slidably retained on side edges of the cover, and a tubular bight at an end of the cover connected to corners of the cover 35 and enclosing the looped portion of the string.

9. A cover for a polishing wheel, consisting of a piece of polishing material having means along

two opposite edges to slidably hold a draw string, a draw string extending through the holding means along one edge, extending out into a bight spaced from the piece, and extending back through the holding means along the other edge, and a bight of flexible inextensible material having its ends fastened to the corners of the piece adjacent the bight of the draw string and slidably held along its length to the bight of the draw string.

5 10. A cover for a polishing wheel, consisting of a piece of polishing material, a continuous tubular stitching fastened along one edge of the piece, extending out into a bight spaced from the piece, and fastened back along the edge parallel to the first edge, and a draw string extending through the tubular stitching along one edge of the piece, around the bight, and back along the other edge.

15 11. A flexible sheet material cover for a polishing wheel having a draw string in the shape of a U including legs and a loop portion, each of said legs being slidably retained on a side edge of the cover by a stitched means, and the loop portion of said U-shaped string extending beyond 20 an end of the cover.

25 12. A flexible sheet material cover for a polishing wheel having a draw string arranged in the shape of a U including legs and a loop portion, each of said legs being slidably connected 30 to a side edge of the cover, and the loop portion of said U-shaped string extending beyond an end of the cover for connection to the polishing wheel preliminary to the application of the cover to the 35 wheel.

ANTHONY CONIGLIO.
